UNITED STATES PATENT OFFICE.

CHARLES M. CONNOLLY, OF TROY, NEW YORK, ASSIGNOR TO CLUETT, PEABODY & CO., INC., OF TROY, NEW YORK, A CORPORATION OF NEW YORK.

COLLAR-DISPLAY DEVICE.

Application filed September 4, 1925. Serial No. 54,454.

In displaying styles of men's collars it has been customary to provide glass cases containing a sample of each style. This practice involves considerable expense in providing cases and sample collars and the cases occupy valuable space. Furthermore, an accurate conception of how a collar will appear in use can not be conveyed by displaying a collar without a tie, but to demonstrate to the customer quickly and clearly how a tie will set on the collar, how high the collar appears with the tie in place, etc., it is necessary to apply ties to the collars. This method of display is so tedious that it is rarely practiced in a retail shop with the consequence that customers are slow in making selections and many orders are returned for exchange.

It has been proposed to employ printed pictures of collars and ties for demonstration purposes but such pictures, while suitable for car advertisements to be viewed at a distance, are not adapted to take the place of real collars and ties for demonstration in retail shops for the reason that they obviously are prints and do not create the impression of the real articles.

Objects of the present invention are to provide, in lieu of real assemblages of collars and ties, a substitute display which creates an optical illusion of the genuine articles even at comparatively short range, which is inexpensive and compact, and which may readily be altered as styles change.

According to this invention a replica of a collar and tie ensemble is embossed in a black or other dark area and the dark area is wholly framed by a light card, thereby to produce the optical illusion of a window in the light card with a real collar and tie in a dark space back of the window. The illusion is enhanced by slightly displacing the dark area from the plane of the front of the card, by making the dark area convex and by providing slits at margins of the dark area so that light may shine through the card around the edges of the dark area. Consequently I preferably form the dark area and embossed replica on a separate smaller card which is mounted in slots in the larger light card with its exposed face convex and with portions of the slots uncovered. While the light slits may wholly surround each dark area the effect is substantially as good if they only extend along each of two opposite sides

of the dark area. The provision of the collar and tie ensemble on a smaller detachable card has the further advantages that it permits the smaller card to be made of thinner material which may be embossed more realistically and also permits new styles to be substituted for obsolete styles by interchanging the small inserts.

For the purpose of illustration a concrete embodiment of the invention is illustrated in the accompanying drawings in which,

Fig. 1 is a front view of the display device:

Fig. 2 is a section on line 2—2 of Fig. 1; and

Fig. 3 is a section on line 3—3 of Fig. 1.

In the particular embodiment chosen for the purpose of illustration A is the larger permanent card which may be yellow and carry suitable indicia, and BB are the smaller detachable cards which have the embossed replica of the collar and tie ensembles and which are preferably dull black. As shown in Figs. 2 and 3 the embossed collars and ties project forwardly from the plane of the cards B and their outlines are rounded in planes perpendicular to the cards; and as shown in Fig. 3 the fold line FF' of the collar stands out throughout the entire circumference of the collar. The ties are appropriately colored and the embossed collar portions are preferably made to simulate the weave, stitching and shadows of genuine collars, partly by printing and partly by minute embossing to represent the interstices between woven threads within the outline of each collar as defined by the heavy embossing.

As illustrated in the drawings the ends of the cards B are inserted through slots C in card A and then bent inwardly, thus detachably securing the cards together and causing the cards B to bow slightly in a forward direction as shown in Fig. 2. The slots C are made wider than the thickness of cards B to provide the aforesaid light slits shown at D. The back may be provided with an easel support E having wings H creased to swing into parallelism with card A.

A display device constructed as aforesaid presents such a striking optical illusion of real collar and tie ensembles that it serves all the purposes of actual collar and ties and with a small fraction of the cost and space.

Indeed the effect is so realistic that many customers examine the display closely and after discovering that the collars are not real, pass their fingers over the front of the display apparently to convince themselves that the effect is truly an illusion.

I claim:

1. A display device comprising a light card having spaced slots extending therethrough, and a dark card bridging the space between said slots and having its ends anchored in said slots with light slits at said ends, the exposed face of the dark card being wholly framed by the light card and being convex and bearing an embossed replica of a collar and tie ensemble, whereby the device presents the optical illusion of an opening in the light card and a real collar and tie in a dark space back of the opening.
2. A display device comprising a light card having spaced slots extending therethrough, and a dark card bridging the space between said slots and having its ends anchored in said slots, the exposed face of the dark card being wholly framed by the light card and bearing an embossed replica of a collar and tie ensemble, whereby the device presents the optical illusion of an opening in the light card and a real collar and tie in a dark space back of the opening.

3. A display device comprising a light card, and a smaller dark card mounted in approximately parallel juxtaposition to one side of the light card with its exposed face wholly framed by the light card, the smaller card having a replica of a collar and tie ensemble embossed within the areas of its exposed face, whereby the device presents the optical illusion of an opening in the light card and a real collar and tie in a dark space back of the opening.

4. A display device comprising a light card, a dark area within the confines of the card and slightly displaced from the plane of the front face of the card, and within the dark area an embossed replica of a collar and tie ensemble, whereby the device presents the optical illusion of an opening in the light card and a real collar and tie in a dark space back of the opening.

5. A display device comprising a light card, a dark area on the card, and within the dark area an embossed replica of a collar and tie ensemble, whereby the device presents the optical illusion of an opening in the light card and a real collar and tie in a dark space back of the opening.

Signed by me at Troy, New York, this 25th day of August, 1925.

CHARLES M. CONNOLLY.
